UNITED STATES PATENT OFFICE.

LUCIEN F. EASTON, OF LA CROSSE, WISCONSIN.

TEMPERATURE-REGULATOR.

SPECIFICATION forming part of Letters Patent No. 430,226, dated June 17, 1890.

Application filed March 4, 1890. Serial No. 342,579. (No model.)

To all whom it may concern:

Be it known that I, LUCIEN F. EASTON, a citizen of the United States, residing at La Crosse, in the county of La Crosse and State 5 of Wisconsin, have invented certain new and useful Improvements in Temperature-Regulators, of which the following is a specification.

My invention consists in a temperature-regulating apparatus of novel construction and arrangement, designed to control the temperature in one apartment or in each of a series of apartments, as required.

In the annexed drawings, Figure 1 is a diagrammatic view illustrating the general construction and arrangement of my improved apparatus; Fig. 2, a sectional view of two of the air vents or valves employed therein.

It is important in apparatus of this character to provide for producing in each apartment the desired degree of temperature before checking the general heat-supply, as otherwise the supply would be cut off from or checked in the several apartments as soon as 25 the desired temperature should be attained in any one of them.

The manner in which I secure the desired result will be readily understood upon again referring to the drawings, in which A, B, and 30 C indicate apartments in which the temperature is to be controlled, each of said apartments being furnished with a valve, damper, or other device D for controlling the supply of heat thereto.

It will of course be understood that it is 35 immaterial what the character of the heating apparatus or of the controlling valve or damper may be, and that the valves D (represented in the drawings) are merely illustrative of the class, and not meant to indicate any one type to the exclusion of others. In other words, the valves D are to be understood as standing for and representing either registers controlling warm-air flues, valves controlling the flow of steam or hot water, or any 40 other well-known device for controlling the heat-supply or ventilation, or the combination of any or all such different devices.

Connected with each of the valves or devices D is a movable diaphragm or a piston a, forming one wall of the shell or chamber of a regulator E, there being a separate regu-

lator for each valve. From the shell or chamber of each regulator E a pipe b passes to an exhausting apparatus of any convenient sort, 55 represented in the drawings in the form of an aspirator F. This well-known device consists, essentially, of a tube through which water flows longitudinally, the bore of the tube being contracted at the point where the pipe b 60 communicates with it. Each pipe b connects independently with exhaust apparatus, and each is furnished with an air-vent c, conveniently formed by an open-ended branch pipe b'. 65

Directly opposite the vent or mouth of each branch pipe b' is a valve plate or disk d, carried by the free end of a compound bar G, or other common form of thermostat, so arranged as to cover and seal the vent c whenever the 70 temperature of the apartment falls so low as to cause a sufficient movement of the bar G in that direction.

So long as the vent c of any one of the pipes b remains open or unsealed the aspirator F of that apartment will merely draw air through said vent, and the diaphragm or piston of the regulator E, with which said vent communicates, being unaffected by the suction of its aspirator F, will fall, either by reason of its weight or that of the valve D, with which it is connected, and cause the closing of the valve and the consequent cutting off of the heat-supply. When, however, the temperature falls below the predetermined 85 limit, the bar G will carry the plate or disk d against the end of pipe b', seal the vent c, and cause the aspirator F to exhaust the air from chamber of regulator E, thereby drawing in the diaphragm or piston a and 90 opening the valve D. In this way a due heat-supply will be admitted.

It will be observed that each of the thermostats G acts independently of the others, and that as a consequence the temperature of 95 each apartment is independently regulated and controlled.

When all the apartments reach the prescribed limit of temperature, it is desirable to check the fire, and for this purpose I provide another aspirator or exhauster H, which communicates by a pipe I with each of a series of vents, one controlled by each of the pipes b.

Between the pipe I and each of the pipes b there is placed an air valve or vent J of the construction illustrated in Fig. 2, said vents serving, when opened, to admit air to pipe I, but at no time admitting air to the pipes b. As shown in said Fig. 2, each air valve or vent J consists of a shell having a flexible diaphragm e, dividing it into two chambers or compartments, the upper one communicating

10 with one of the pipes b and the lower communicating with pipe I.

The diaphragm e of each air valve or vent J is normally pressed against and made to seal the mouth of the pipe f, by which communication is established between the lower chamber or compartment of the valve casing or shell and pipe I by a spring K, so that air cannot enter pipe I through said valve or vent until the diaphragm is lifted off the

15 mouth of pipe f. When, however, the vent c in any one of the apartments A B C is sealed, the aspirator F of that apartment first exhausts the air from the chamber of regulator E and opens valve D, and then by its fur-

20 ther action exhausts the air from the shell or casing of the air valve or vent J belonging to said apartment, causing its diaphragm to rise in opposition to spring K and to unseal the mouth of pipe f, thus permitting air to pass

25 through said pipe into pipe I, and thence to exhauster or aspirator H, the air entering the shells J through inlets g. It is obvious that the exhauster F may be made to open the vent-valve to the pipe I before opening the valve

30 or register D for the admission of heat to the room, and in case of an indirect radiator of a steam-heating apparatus such action is preferable. So long therefore as the temperature in any apartment remains low enough to ne-

35 cessitate the opening of the warm-air-supply valve the pipe I will be vented.

Whenever the temperature is raised to the prescribed limit in all the apartments, all the vents c will be opened, and consequently the 40 diaphragm e of all the air-valves J will be seated by their springs upon the pipes or air-inlets f, thereby preventing the admission of air to pipe I and enabling the aspirator or exhauster H to exhaust the air therefrom.

45 L indicates a regulator of the same general type as the regulators E, and, like them, provided with a flexible diaphragm or piston h, which is connected either directly or indirectly with a check, valve, or damper M, for 50 checking the fire of the furnace, boiler, or heater supplying heat to the apartments A B C.

The aspirator or exhauster H, by exhausting the air from above the diaphragm or piston h, causes it to be drawn in, and thereby to open the check or close the draft, or both, and thereby to check the fire.

55 In Fig. 1 I have shown the regulator-diaphragm h combined with an ordinary steam-regulating diaphragm; but it is manifestly immaterial what particular form of check or draft apparatus be employed, such being well

known and commonly used in a variety of forms, of which I have illustrated one.

Whenever the temperature of any one of the apartments A, B, or C again falls so low as to cause the closing of its vent c, its aspirator F will first act upon the piston or diaphragm of its regulator E and open the warm-air valve D, thereby admitting a supply sufficient to restore the temperature to its proper point. If this requires only a brief opening, the action may take place without affecting the air valve or vent J of the particular regulator E actuated; but if the heat-supply is not such as to speedily restore the temperature the suction in pipe b will become sufficient to raise the diaphragm e of the air valve or vent J, thereby admitting air to pipe I, destroying the vacuum in 85 regulator or chamber L, and permitting its diaphragm or piston to drop, and thereby close or permit the closing of check M, the opening of the draft, or both.

The apparatus is very simple and cheap in 90 construction and is efficient and sensitive in action.

It will be seen that the springs K may be omitted; but if this be done the diaphragm e should be made heavy enough to close by 95 gravity when relieved from suction above them. So, too, the several regulators E may all connect with a single exhauster or exhausted chamber, or the separate exhausters and the air-vents may be grouped at a common point.

Although I have described and shown opening of registers or valves by vacuum and the closing of some by gravity or springs, it is obvious that this action may be reversed, it 105 only being necessary to arrange the thermostat G so that an increase of temperature in the apartments will cause the closing of vent c. The action of the exhauster H must then be reversed, so as to cause an increase of combustion in the heat-generator when the valves or registers are opened by spring or weight. This modification is preferable in the regulation of hot-air furnaces; but in steam the 110 vacuum should close the furnace-drafts, and when the vacuum is destroyed the ordinary well-known steam-regulator operates to carry 115 the desired steam-pressure.

Having thus described my invention, I 120 claim—

1. In combination with two or more apartments, each provided with a valve for controlling the supply of heat, regulators—one for each apartment—each comprising a shell and a movable diaphragm or piston and suitable connections between the diaphragm or piston and the valve, exhausting apparatus connected separately with each of the regulators, an air-vent for each regulator, a thermostatic valve controlling each of said vents, 125 a valve or damper for controlling the generation of heat, a regulator having a diaphragm or piston connected with said valve or damper, a pipe extending from said regulator to an 130

exhausting apparatus, and air valves or vents opening into said pipe, and each having a valve subject to the suction controlling the regulators in the several apartments, whereby 5 the valves controlling the admission of heat to the apartments are opened or closed, as required, and the generation of heat is checked whenever all the apartments reach the pre-determined temperature and increased when 10 any apartment falls below a predetermined limit.

2. In combination with a heat-supply valve, and a regulator connected with and serving to control the same, an air-vent opening into 15 said regulator, a thermostatic valve controlling said vent, an exhauster communicating with said regulator, a heat-generator, a valve or damper controlling the generation of heat, a second regulator connected with the generator 20 valve or damper, an exhauster communicating with the regulator of the generator valve or damper, and an air-valve for admitting air to said regulator when open, said valve being subject to the suction upon the 25 heat-supply valve, whereby the heat-supply valve and the generator-valve are operated successively.

3. In a temperature-regulating apparatus, the combination, with a heat-generator and a 30 valve or damper controlling the generation of heat therein, of a regulator, substantially such as described, connected with and controlling the adjustment of said valve or damper, an exhauster communicating with the regulator, 35 an air valve or vent also communicating with said regulator, and a thermostatically-controlled device located in the apartment in which the temperature is to be regulated, and serving to control the opening and closing of 40 said air valve or vent.

4. In a temperature-regulating apparatus, the combination of a heat-generator, a valve

controlling the generation of heat therein, a heat-supply valve for controlling the admission of heat to an apartment, independent 45 regulators for said valves, each connected with exhausting apparatus, and an air valve or vent adapted to be opened by the exhaust or suction upon the heat-supply regulator, and serving when opened to admit air to the 50 generator-regulator.

5. The herein-described air valve or vent for temperature-regulators, consisting of a shell provided with a flexible diaphragm *e*, a pipe or outlet *f*, and inlets *g*. 55

6. In combination with a shell open at one side for communication with an exhauster, a pipe or outlet *f* and inlets *g* at the opposite side of the shell, an intermediate flexible diaphragm *e*, and a spring *K*, bearing upon the 60 diaphragm and tending to press the same upon the mouth of the outlet *f*.

7. Two or more expansible and contractible chambers, each operating, by such contraction or expansion, one or more valves, dampers, 65 &c., an exhausting apparatus, and an air-inlet communicating with each of the said expansible and contractible chambers, a thermal valve controlling each of said inlets, a second expansible and contractible chamber 70 communicating with each of said exhausters, a valve operated by each of said expansible and contractible chambers, each of said valves serving to control an air-inlet to another expansible and contractible chamber, said last-named chamber operating the valves, dampers, &c., of a heat-generator, and having an exhauster in communication with it. 75

In witness whereof I hereunto set my hand in the presence of two witnesses.
